(57) **CLAIM**

The ornamental design for a knee pad as shown and described.

DESCRIPTION

FIG. 1 is a perspective view of a knee pad showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of another knee pad showing the new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

Broken lines showing the "TRUEWERK" branding in FIGS. 1-2, 4-9, and 11-14, as well as broken lines showing through holes in FIGS. 8-14, form no part of the claimed design. The "TRUEWERK" lettering and icon shown in broken lines is a registered trademark of Truewerk, Inc.

1 Claim, 10 Drawing Sheets
